UNITED STATES PATENT OFFICE.

JESSE L. JACOBUS, OF NEWARK, NEW JERSEY.

RADIATOR-VENT VALVE.

Application filed April 10, 1928. Serial No. 268,870.

This invention relates to valves for venting air from radiators of steam heating systems, and more particularly the invention concerns valves of this general character which are 5 so constructed as to prevent entrance of air into the radiators when the pressure therein falls below atmospheric pressure.

One object of the invention is to provide a radiator venting valve of the character described embodying novel and improved features of construction including a valve which automatically seats itself upon reduction in pressure in the radiator below atmospheric, which is positively held seated by a thermostatic element as steam enters the valve to prevent escape of steam from the radiator and is released by said thermostatic element as steam leaves the radiator so that the valve may be unseated to permit escape of air as 20 may be necessary upon influx of steam pressure into the radiator.

Another object is to provide such a valve including a novel and improved disc valve element and seat whereby tendency to sticking of the valve on its seat is practically eliminated, so that the valve element is extremely sensitive to pressure within the radiator and easily and quickly unseats to permit escape of air from the radiator.

30 Further objects are to provide a radiator vent valve including a novel and improved form of construction and combination of valve element and thermostatic element, whereby the valve is extremely sensitive and reliable in operation; to provide a disc valve element cooperating with an annular seat and to so arrange said disc valve element that its normal tendency is to automatically, by action of gravity, disengage itself from the seat; to provide novel and improved means for locking such a valve against unauthorized removal from a radiator; to provide a valve of this character, which is simple and inexpensive in construction and is 45 easily accessible for adjustment or repair, and to obtain other results and advantages which will be brought out in the following description.

Referring to the accompanying drawings, 50 in which corresponding and like parts are designated throughout the several views by the same reference characters,

Figure 1 is an enlarged vertical sectional view through a radiator vent valve embodying my invention, showing the same attached

to a radiator which is fragmentarily illustrated, the parts being shown in the position assumed when steam is in the valve casing.

Figure 2 is a horizontal sectional view taken on the line 2—2 of Figure 1, and 60

Figure 3 is a horizontal sectional view taken on the line 3—3 of Figure 1, the valve being shown with the parts in the position assumed when the valve is cold and the valve element held to its seat by vacuum within the 65 radiator.

Specifically describing the illustrated embodiment of my invention, the reference character A designates the casing of the valve which includes a base section 1 having a laterally projecting nipple 2 for attachment to the radiator B. The passage through the nipple 2 communicates through openings 3 with the interior of the main section 4 of the casing, which has a threaded connection 70 5 with the base section 1. The outside of the top of the main section 4 has a boss 6 provided with an axial opening 7 communicating at one end with the interior of the section 4 and with which cooperates a valve 8 actuated by 75 a float 80 so that upon influx of water into the casing A, the passage 7 is closed to prevent outflow of water from the valve. A lateral passage 9 in the boss 6 has at one end an annular sharp-edged ridge serving as a 80 valve seat 10 with which cooperates a disc 85 valve 11 formed of a thin circular sheet of non-corrosive metal. The valve seat is arranged at the base of a valve chamber or recess 12 formed in the side of the boss 6, and the valve disc 11 is held within said chamber 90 by a thermostatic element 13.

This thermostatic element is of any suitable construction, preferably laminated with metals having different coefficients of expansion, and is in the form of a curved band surrounding the boss 6 with one end fast secured to the boss as at 14, and the other end provided with a bearing head 15 to abuttingly contact with the valve disc 11. The boss 6 and thermostatic element 13 are enclosed by a top section or cap 16 which has a screw threaded connection 17 with the main section 4 of the casing A, said top section having vent openings 18 to permit escape of air from 100 the casing.

In operation, the valve is applied to the radiator with the casing A in vertical position, that is with the axis of the casing disposed vertically. The valve disc 11 is thus disposed in 105 110

a vertical plane and rests at its lower edge upon the side of the valve chamber 12 as clearly shown in Figure 1 of the drawings. The valve disc in effect floats in the chamber 12 between the valve seat 10 and the bearing head 15 on the thermostatic element, and when the radiator is cold and a partial vacuum obtains therein the valve disc 11 is held to its seat by suction as shown in Figure 3, the thermostatic element being contracted so that the bearing head 15 is in spaced relation to the valve disc. As steam enters the radiator, and assuming that air is present, the valve disc 11 will be forced from its seat by the pressure of the outgoing air, and the air will escape through the vent openings 18. When steam enters the valve casing the thermostatic element expands so that the bearing head 15 is moved inwardly into contact with the valve disc and forces and holds the latter in tight engagement with the valve seat to prevent the escape of steam.

It will be observed that the normal tendency of the valve disc is to fall away from the valve seat 10, so that there is a minimum of resistance to the outflow of air. Furthermore, the valve seat 10 is of small area and large diameter so that a considerable area of the valve disc is exposed to the pressure of the air which further overcomes the resistance of the valve disc to movement away from the valve seat. A valve constructed in accordance with my invention has been found to be extremely sensitive and reliable in operation. The valve is quickly responsive to suction within the radiator, and in combination with the valve seat 10 is also quickly responsive to pressure within the radiator; and its normal tendency to unseat itself by gravity minimizes the tendency of the valve disc to stick on the valve seat.

It is desirable to provide means for locking the valve against unauthorized removal from the radiator. For this purpose I provide two set screws 19 in the base section 1 of the casing, said screws being arranged in a common axial plane of the nipple 2 and one thereof being disposed at each side of said nipple as clearly shown in Figure 2. The base section is formed with a reenforcing rib 20 in which the set screws are mounted, and with this construction it will be observed that after the valve nipple 2 has been screwed into the radiator and the two set screws 19 tightened against the outside of the radiator, the valve nipple cannot be turned without loosening both the screws 19. The particular relative arrangement of the screws and the nipple enables a balancing of the strain imposed on the nipple by the screws, so that all lateral strains such as would tend to bend the nipple may be avoided.

It is also desirable to provide a water return tube 21 in the valve which is disposed with the passage of the nipple 2 and communicates with the openings 3 so that the water may return

through said tube without interference with the steam passing into the casing A through the nipple 2.

While I have shown and described my valve as embodying certain details of construction 70 it will be understood that this is primarily for the purpose of illustrating the principles of the invention and that many modifications and changes may be made in the details of construction without departing from the 75 spirit or scope of the invention.

Having thus described my invention, what I claim is:

1. A valve of the character described comprising a casing having an inlet and an outlet surrounded by an outwardly facing valve seat in the form of an annular sharp-edged ridge arranged so as to be in a substantially vertical plane when the valve is in operation, a valve disc cooperating with the seat, there being means for supporting said disc edge-wise and permitting movement thereof toward and from said seat, and a thermostatic element in said casing to have a separable abutting contact with said disc so as to permit said disc to independently move against said seat and away therefrom under pressure from within said casing and under influence of gravity when the valve is cool and force and hold said disc against said seat when the valve is at a predetermined higher temperature.

2. A valve of the character described comprising a casing having an inlet and an outlet opening surrounded by a valve seat in the form of an annular sharp-edged ridge disposed at the base of a recess outward of said opening, a valve disc arranged in said recess to cooperate with said valve seat, said disc being normally disposed in a vertical plane 105 and resting edge-wise upon the side wall of said recess, and a thermostatic element in said casing to have a separable abutting contact with said disc so as to permit said disc to independently move against said seat and away therefrom under pressure from within said casing and under influence of gravity when the valve is cool and force and hold said disc against said seat when the valve is at a predetermined higher temperature.

3. A valve of the character described comprising a casing having an inlet and a boss having an outlet passage opening through one side of said boss surrounded by a valve seat normally disposed in a vertical plane, a valve disc cooperating with said seat, there being means for supporting said disc edge-wise and permitting movement thereof toward and from said seat, and a curved laminated thermostatic element secured at one end to said boss and surrounding the boss with the other end having a separable abutting contact with said disc so as to permit said disc to independently move against said seat under influence of partial vacuum within said

casing and away from said seat under influence of pressure within said casing and action of gravity when the valve is cool, the second-mentioned end of said thermostatic element being moved to force and hold said disc against said seat when the valve is at a predetermined higher temperature.

4. A valve of the character described comprising a casing having an inlet and a boss 10 having an outlet passage opening through one side of said boss surrounded by a valve seat, disposed at the base of a recess outward of said opening, a valve disc arranged in said recess to cooperate with said seat, said disc 15 being normally disposed in a vertical plane and resting edgewise upon the side wall of

said recess, and a curved laminated thermostatic element secured at one end to said boss and surrounding the boss with the other end having a separable abutting contact with said disc so as to permit said disc to independently move against said seat under influence of partial vacuum within said casing and away from said seat under influence of pressure within said casing and action of gravity when the valve is cool, the second-mentioned end of said thermostatic element being moved to force and hold said disc against said seat when the valve is at a predetermined higher temperature.

JESSE L. JACOBUS.
